MULTIFLOOR FEEDERS

Marvin L. Smallegan, Zeeland, Mich., assignor to Automatic Poultry Feeder Company, Zeeland, Mich., a corporation of Michigan

Application August 25, 1953, Serial No. 376,410

6 Claims. (Cl. 198—85)

This invention relates to feeders and more particularly to a feeder designed to operate simultaneously upon several floors, with the feed supplied to the feed distribution means on all of the floors from a single hopper on the ground floor.

The expansion of the poultry business has made it necessary and desirable to build multi-floor poultry houses. While this is a saving in total ground area utilized and is economical in the original investment, it has always presented serious difficulties when it came to properly and adequately feeding the poultry on the upper floors. While the provision of water on the upper floors was simple, because it could be moved through pipes under pressure, the movement of the dry feed to the upper floors remained a problem which, until this invention, had never been satisfactorily solved.

Heretofore it has been necessary to provide storage hoppers for the feed on each of the floors. Each of these hoppers had to be individually supplied. This necessitated the transportation of the bulk feed to these upper floors, either manually or mechanically by means of winches or elevators. Whatever method was used to elevate the feed, this handling of the feed required much manual labor and consumed many man hours. It eliminated the possibility of supplying the feed to the hoppers from bulk trucks in which the feed was loaded directly from large storage bins without first sacking it in containers of limited size and weight such as 100 pound units.

Further, the use of storage bins on each of the separate floors necessitated the use of much bulky equipment eliminated by my invention. Not only was it necessary to provide this bulky equipment but it was also necessary to be sure the floors were adequate to support the concentrated loads imposed by these hoppers when fully loaded. The operators had to periodically climb to the upper floors to inspect the hoppers to make sure that sufficient feed was present to adequately supply the poultry.

My invention solves this difficult problem by a simple, efficient and reliable arrangement. It makes it possible to completely and adequately supply simultaneously any one or all of a large number of floors with adequate supplies of feed using a single bulk hopper located on the ground floor. Thus, my invention makes it possible to eliminate the elevation of all bulk feed to upper floors. It also eliminates the necessity for storage hoppers on the upper floors. It further eliminates all necessity for the operators inspecting the upper floor feeder to make sure they are adequately supplied. All of these operations can be properly attended to on the first floor alone.

These and other objects and purposes of my invention will be readily seen by those acquainted with the construction of poultry feeding equipment upon reading the following specification and the accompanying drawings.

In the drawings:

Fig. 1 is a side elevation view of my invention.

Fig. 2 is a sectional plan view of the ground floor hopper for my invention taken along the plane II—II of Fig. 3.

Fig. 8 is a fragmentary, sectional view of the feed elevator.

Fig. 9 is a sectional view taken along the plane IX—IX of Fig. 8.

Fig. 10 is an enlarged, sectional view taken along the plane X—X of Fig. 4.

Fig. 11 is a sectional, elevation view taken along the plane XI—XI of Fig. 10.

In executing the objects and purposes of my invention, I have provided a machine having a bulk feed hopper on the ground floor. The bulk feed hopper is designed to distribute feed through multiple troughs to poultry on the ground floor. The feed is removed from the main storage bin in the ground floor hopper and discharged onto the distribution chains of the troughs on the ground floor. Excess feed, after passing across the chains, is discharged into an elevator.

The machine is so arranged that substantial excess quantities of feed pass into the elevator after passing over the chains on the ground floor. This feed is elevated to a point above the feed distribution means on the top one of the several floors to be supplied. There the feed is discharged from the elevator into a chute where it may either be caused to by-pass the distribution means on that floor and dropped to the next floor below or it may be discharged into a feed distribution means on the top floor. If it is discharged into the distribution means on the top floor, it is moved across the feed distribution chains on that floor in the same manner as it was originally moved across the distribution chains on the ground floor.

A quantity of feed is supplied to the top floor that is substantially in excess of the requirements of the feed distribution chains on that floor. This excess feed is discharged into a chute and dropped to a similar feed distribution means on the next floor below. Again, means are provided whereby the feed may either be caused to by-pass that floor or discharged into the distribution means. Any excess feed from this distribution means is returned to the chute where it drops either to the next floor below or it is returned to conveyor means mounted above the hopper on the first floor. This remaining feed is screened and returned to the feed bin on the first floor.

Referring specifically to the drawings, the numeral 10 indicates a hopper having a bulk feed bin 11 (Fig. 2) the bottom of which is formed by a sloping panel 12 (Figs. 1 and 2). The inclined panel extends downwardly toward one side of the hopper forming a channel 13. The inclination of the panel 12 causes the feed to slide down into the channel 13 where it is operated upon by the supply conveyor 14. The supply conveyor 14 consists of a shaft 15 surrounded by a helically coiled rod 16 which, upon rotation of the shaft 15, serves to move the feed toward one end of the channel 13. The rod 16 is spaced an appreciable distance from the shaft 15 thereby making the supply conveyor 14 largely a hollow structure.

To one side of the feed bin 11 and within the hopper structure 10 is a feed distribution chamber 20 separated from the hopper by a vertical panel. At the discharge end of the supply conveyor 14 the panel between the feed bin 11 and the distribution chamber 20 is apertured. The shaft 15 passes through this aperture and across the dis-

tribution chamber. Where the shaft 15 crosses the distribution chamber 20, it mounts a distribution conveyor 21. The distribution conveyor 21 consists of a pair of diametrically opposed, rigid helical flanges 22. Detachably mounted to each of the flanges 22 is a radially projecting, flexible flange 23. The flange 23 may be made from any suitable, wear-resistant, flexible material, preferably a rubber of medium durometer test or a rubber and fabric combination. The overall diameter of the distribution conveyor 21 is somewhat greater than the overall diameter of the supply conveyor 14. The purpose of this will appear more fully hereinafter. The pitch of the distribution conveyor 21 is from three to five times greater than the pitch of the supply conveyor 14. The purpose of this will also appear more fully hereinafter. Since the rigid flanges 22 are securely affixed to the shaft 15, the distribution conveyor 21 rotates with the shaft 15 and, thus revolves at the same speed as the supply conveyor 14.

Passing through the distribution chamber 20 in a direction normal to the shaft 15 is a plurality of feed distribution chains 24. The feed distribution chains 24 are, throughout a substantial portion of their length, confined within open topped troughs 25. The chains 24 serve to carry the feed out of the distribution chamber and along the troughs where it is available to the poultry. That feed which is not used by the poultry is returned by the chains 24 to the distribution chamber at a point adjacent the distribution conveyor 21. Chain of any suitable construction may be used for the distribution chains 24. Preferably, it is a flat chain suitable for movement around corners without rotation about its longitudinal axis. Further description of this chain is not believed necessary since its structural details constitute no part of this invention.

On the side of the distribution chamber 20, remote from the feed bin 11, is an elevator 30. The elevator 30, at its bottom end, communicates with the distribution chamber 20 by means of an opening through the wall 31 separating the distribution chamber from the elevator 30 and from the side compartment 32. The aperture through the wall 31 is aligned with the shaft 15 and is at the discharge end of the distribution conveyor 21.

The shaft 15 extends through the wall 31 across the elevator 30 in compartment 32. Within the elevator the shaft 15 mounts a sprocket 33 functioning as the lower end and driving means for the elevator chain 34. The elevator chain 34 is of conventional construction, having a plurality of spaced flights 35 (Figs. 8 and 9) attached to the chain by means of lugs 36. Each of the flights 35 is of such a size that it entirely occupies the housing 37 within which the elevator 30 is confined. Further description of the elevator chain 34 and the flights 35 is not believed necessary since any one of a number of commercially available chain designs suitable for this purpose may be used. Further, the structural details of the chain and its flights constitute no part of this invention.

The elevator 30 is so driven that the chain 34 moves downwardly through the elevator column 38 and upwardly through the elevator column 39 (Fig. 1). The length of the columns 38 and 39 is dependent upon the number of floors to be supplied by the unit. It is fabricated in detachable lengths, secured by bolts passing through the flanges at each end with as many lengths being used as are needed. The columns 38 and 39 are joined at their upper ends by a header 41 containing an idler sprocket mounted on a shaft 42. At this end, the elevator chain 34 discharges through an opening in the bottom of the header 41 into a funnel 43.

The end of the shaft 15 in the end compartment 32 mounts a pulley 50. The pulley 50 is connected by a belt 51 to a driven pulley 52 on the end of the shaft 53.

The belt 51 also passes over a pulley 54 mounted on the shaft 55. The shaft 55 operates an anti-bridging agitator within the feed bin 11. This agitator forms no part of this invention, and consequently is neither illus-

trated nor described. The belt 51 is tensioned by means of an idler 56 mounted on the pivoted arm 57. The idler 56 is urged against the belt 51 by the spring 58. The shaft 53 extends across the distribution chamber 20 into the power compartment 60 (Fig. 3). In the distribution chamber 20 a plurality of sprockets 61 are mounted on the shaft 52. Each of the sprockets 61 is aligned with one of the distribution chains 24 and engages the chain 24 to drive it. The sprockets are all tightly secured to the shaft 53 whereby operation of the shaft will drive all of the sprockets simultaneously.

Immediately adjacent the distribution conveyor 21 and between it and the sprockets 61 is a semi-rigid, vertically adjustable gate 72 (Fig. 2). The gate 72 is secured to the panel 73 by studs passing through slots in the panel 73. The studs are locked to the panel 73 by wing nuts 74. The purpose of the gate 72 will be fully described under "Operation."

The shaft 53 is driven by means of a chain 63 connecting it to the speed reducer 64. The speed reducer 64 is connected to a prime mover 65 by means of a belt 66. Although it is not shown, a variable speed pulley arrangement may be interposed between the prime mover 65 and the speed reducer 64 whereby the speed of the machine may be quickly varied by the operator. The prime mover 65 serves as the sole source of power for driving all of the feed distribution chains 24 on the ground floor, the elevator 30 and the supply conveyor 14 and the distribution conveyor 21. The use of this single power source substantially reduces the overall cost of the machine.

Where the distribution chains 24 enter and leave the distribution chamber 20, they are enclosed by a guard 67 to prevent poultry from being accidentally drawn into the operating mechanism within the hopper. The guards 67 each have a removable cover 68 detachably held by the looped rods 69. The front and back ends of the distribution chamber 20 are closed to keep out poultry and to prevent dirt from getting into the feed and mechanism in this area. While the power compartment 60 is shown as open, it is likewise closed by a removable panel.

The feed discharged from the elevator 30 into the funnel 43 falls by gravity into the confined chute 80. The confined chute 80 is a tube mounted to the side of the upper floor distributor unit 81. The chute 80 communicates directly with the feed chamber 82 in the distributor 81 through the opening 83 (Fig. 6). Mounted in the top end of the chute 80 at each of the distributors 81 is a baffle 84 secured to a rod 85 at its upper end. The rod projects through the walls of the chute 80 and has a handle 86 on its outer end (Fig. 7). The baffle 84 may be moved from a hanging position within the chute 80 (indicated by the broken lines in Fig. 6) to a sharply inclined position extending through the opening 83 (shown in full lines in Fig. 6) where it will direct feed from the chute 80 or the funnel 43 into the feed chamber 82. The rod 85 is located immediately adjacent the wall of the chute 80 remote from the feed chamber 82, permitting the baffle 84 to accomplish its purpose. The baffle is held in inclined position by moving one leg of the latch 88 out under the handle (Fig. 7).

The feed chamber 82 is supported within the distributor unit 81. At its lower end it has a narrow, slot-like discharge opening 90. The discharge opening 90 discharges into the distribution chamber 91 through which pass the distribution chains 92. The direction of the distribution chains 92 is normal to the axis of the discharge opening 90. These chains are identical in construction to the distribution chains 24 used on the ground floor.

Immediately beneath the discharge opening 90 is a distribution conveyor 93, identical to the distribution conveyor 21, and consisting of a pair of diametrically opposed, rigid, helical flanges 22a (Fig. 10) each having a radially projecting, semi-flexible, peripheral flange 23a

attached to the rigid flange 22a by suitable fasteners such as bolts 94. The rigid flanges 22a and semi-flexible flanges 23a are identical to the corresponding flanges 22 and 23 of the distribution conveyor 21. The distribution conveyor 93 has the same pitch as the distribution conveyor 21.

The distribution conveyor 93 is mounted on a shaft 95. To one side of the distribution chamber 91 is a power chamber 96 (Fig. 4). One end of the shaft 95 extends into the power chamber 96 and mounts a pulley 97. The other end of the shaft 95 extends across the chute 80 and is journaled in a bearing 98 in the side of the chute (Fig. 1). The distribution conveyor 93 moves the feed toward the chute 80 and discharges unused feed through an opening at the end of the conveyor into the chute 80. The aperture between the distribution chamber 91 and the chute 80 is large enough to readily pass all excess feed which may be moved by the distribution conveyor 93.

The forward wall 100 of the feed chamber 92, at the point where the feed chamber 82 discharges through the opening 90, is offset forwardly to form the depending panel 101 (Fig. 10). The panel 101 is provided with a pair of slots 102 (Fig. 11) through which pass the studs 103. The studs 103 pass through a semi-rigid, rubber gate 104 and terminate in a rigid bar 105 secured to the back of the gate 104. The gate 104 is made vertically adjustable by means of the slots 102 and is locked in any desirable, vertical position by wing nuts 106 cooperating with the studs 103. The gate 104 extends substantially entirely across the distribution chamber 91 immediately above the distribution chains 92. A slight gap is maintained between the ends of the gate 104 and the sides of the distribution chamber 91 to permit inclination of the gate when it is desired to vary the height of the feed removed from the distribution chamber by the chains. The gate 104 serves the same purpose in the distributor units 81 as the gate 72 serves in the ground floor hopper 10.

Forward of the gate 104 are a plurality of pulleys 110 mounted on a common shaft 111. Each of the pulleys 110 engages and drives one of the distribution chains 92. The shaft 111 is driven by a chain 112 connected to the speed reducer 113. The speed reducer 113 is in turn operated by the prime mover 114 through the belt 115.

The shaft 111 also mounts a pulley 120 over which passes the belt 121. The belt 121 drives the pulley 97 and thus the distribution conveyor 93. The belt 121 is properly tensioned by means of the idler pulley 122. The idler pulley 122 is mounted for vertical adjustment in a slot in the panel 123 separating the forward end of the distribution chamber 91 from the power chamber 96. It is thus seen that on each of the upper floors where there is a distributor unit 81, a single prime mover 114 serves as the sole source of power to operate the distribution conveyor 93 and the distribution chains 92. Thus, only one additional prime mover is needed for each floor supplied by my system.

The distribution chains 92, like the distribution chains 24, are throughout their length, except the short area within the distribution chamber 91, enclosed in open topped troughs 125. Where the distribution chains 92 enter and exit the distribution units 81, guards 126 are provided to prevent poultry from becoming entangled with the mechanism within the chamber. The guards 126 are identical in every way with the guards 67 of the hopper 10 on the ground floor.

The chute 80 is normally rectangular where it lays beside one of the distribution units 81. Although it may be rectangular throughout its length, where it passes through a floor 130 to connect the distribution units 81, it is frequently of circular construction such as the tubular sections 80a shown in Fig. 1. The feed discharged from the last of the distribution units 81 passes down through the tubular portion 80a of the chute 80 and is discharged into the conveyor 150 (Figs. 1 and 3).

The conveyor 150 consists of a helical member 151 75

mounted upon and rotated by a shaft 152 driven by the belt 153 (Fig. 1). The belt 153 is, in turn, driven by a pulley 154 mounted on the end of the shaft 55. The conveyor 150 extends above and across the hopper 10.

At the end of the hopper 10 remote from the distribution chamber 20 it terminates in a screen 155. The screen 155 is mounted on the shaft 152 and is rotated thereby. The screen 155 is so constructed that feed will pass through it into the feed bin 11. Any trash, litter or other foreign material which may have become intermixed with the feed, is retained by the screen and discharged through its open, outer end 156. The discharge end 156 of the screen 155 is beyond the end of the hopper and thus discharges this trash where it will not be returned to the feed bin 11.

While I have described a preferred embodiment of my invention, it will be recognized that various modifications of this construction may be made, all embodying the principles of my invention. Each of these modifications is to be considered as coming within my above disclosure. It will also be recognized that while I have described my invention as specifically applicable to poultry feeders, that it has other uses where it is desired to distribute a finely divided material to individually operated units on a plurality of floors and at the same time eliminate the necessity for providing bulk hopper units or other supply containers on the upper floors.

Operation

30 The bulk feed to supply the entire unit is placed in the feed bin 11 of the hopper 10. This bulk feed serves as the bulk supply for all of the units. Therefore, only the feed bin 11 on the ground floor need be supplied, the machine doing the rest of the work by elevating the necessary quantities of feed to supply the upper floor units.

This feed is slowly removed from the feed bin 11 by the supply conveyor 14. The feed is discharged by the supply conveyor 14 into the distribution chamber 20 where it is immediately acted upon by the distribution conveyor 21. The large pitch of the distribution conveyor 21 moves the feed rapidly across the distribution chamber 20. As much of the feed as is necessary to supply the distribution chains 24 remains on the chains, the rest of it being discharged into the elevator 30.

Since the operation of the distribution conveyor 21 is identical to the operation of the distribution conveyor 93 on the upper floors, it will be described with reference to the disclosure in Fig. 10. The feed discharged into the distribution chamber 20 piles up on the chains and by means of the distribution conveyor 21 is rolled up into the area between the distribution conveyor 93 and the gate 104 forming a pile of feed 160 extending the entire length of the distribution conveyor. A portion 55 of this feed is carried out as a stream 161 by the chains as they move under the gate 104. The height of the gate determines the height of the stream of feed 161.

The pile of feed 160 is constantly agitated and its upper portion 162 is rolled over and over. Because of this rolling action, litter, trash and other foreign materials will be caused to collect in this top portion where they will not be removed by the chains. This litter and trash is quickly carried to the elevator where it is discharged and removed. Any litter or trash which gets into this feed does so by reason of excess feed returned by the distribution chains from the troughs. Thus, the rotation of the distribution conveyors serves to completely clean the feed before any feed is discharged from the distribution chamber onto the chains.

70 The excess feed discharged from the distribution chamber 20 is elevated by the elevator 30. On the top floor this feed is discharged into the funnel 43. The feed discharged into the funnel 43 falls into the chute 80.

Depending upon the position of the baffle 84, the feed either passes down the chute 80 to by-pass the distribu-

tion unit 81 on the top floor or is deflected to cascade into the feed chamber 82. The baffle 84 causes the feed to enter the feed chamber at the far end where it passes through the narrow opening 90. The feed falls from the feed chamber 82 into the distribution chamber 90 between the gate 104 and the distribution conveyor 93. There it is carried along and mixed with any feed which may have been returned by the distribution chains 92.

As on the first floor, any litter or foreign materials returned from the troughs by the distribution chains 92 is collected in the top of the mass of feed 160 between the distribution conveyor 93 and the gate 104. This trash is discharged along with excess feed at the end of the distribution conveyor 93 into the chute 80 where it drops to the distribution unit 81 on the floor below.

The distribution conveyor 93 moves the feed rapidly across the chains 92. The height of the gate 104 determines the amount of feed leaving the distribution chamber and carried out by the chains to supply the troughs. The excess feed discharged by the distribution conveyor 93 to the chute 80 on the top floor is calculated to be enough to at least adequately supply the chains 92 passing through the distribution unit 81 on the floor below.

Any excess feed together with the accumulated trash from all of the distribution units and the hopper 10 is discharged from the bottom distribution unit 81 into the chute 80 which guides it by means of the chute 80a into the conveyor 150. The conveyor 150 transports this feed across the top of the hopper 10 into the screening unit 155. In the screening unit, the feed is separated from the trash and returned to the end of the feed bin 11 remote from the distribution chamber 29. The trash is discharged at the end of the screening unit 155 whereby it is entirely removed from the feed.

It is seen from this description that the feed makes a complete circuit with only that much of the feed remaining on any one of the floors at any one time to adequately supply the system on that floor. Any excess feed is immediately removed and discharged to the feeding unit on the next lower floor. The excess feed discharged from the last of these units is returned to the bulk feed bin 11. Thus, there is no storage of feed on any floor other than the first floor. At the same time, all floors are adequately supplied and this can be quickly determined by an operator on the first floor by inspection.

If, as a consistent condition, no feed is being returned by the conveyor 150, the supply to the upper floors should be increased to be sure they are adequately supplied. This may be quickly done by changing the pulleys 52 and 50 to increase the angular velocity of the supply conveyor 14 and the distribution conveyor 21. By this means, more feed is moved out of the feed bin 11. Since the demand of the chains 24 will remain relatively constant because the angular velocity of the sprocket 61 is not changed, the additional feed discharged by the supply conveyor 14 is discharged into the elevator to serve as a supply for the units on the upper floors.

Since the distribution system on each of the floors is separately powered, any floor may be by-passed when desired simply by shutting off the prime mover 114 on that floor and moving the baffle 84 to down position whereby the feed simply bypasses that floor by dropping down the chute 80 without being deflected into the feed chamber 82.

To avoid injury to personnel servicing this equipment, it has been found desirable to wire the prime mover 65 of the hopper 10 by switches mounted one on each of the floors supplied by the unit. Thus, the prime mover 65 cannot be operated unless all of these switches are closed. This prevents personnel working on upper floors from being injured by accidental closing of a single switch on the main floor to operate the elevator 30.

It will be recognized that suitable switches for operating the prime movers 114 on the upper floors may also be provided both on the particular floor involved and on the first floor to avoid the necessity of making personnel climb to the upper floors when it is desired to activate or inactivate a particular distribution unit 81. It will be further recognized that to make this system fully automatic and controllable from the first floor, suitable solenoids might be provided to operate each of the baffles 84. These solenoids could be operated by three way switches with one unit provided on the floor involved and one unit provided adjacent the hopper on the first floor. With these various additions the entire unit may be entirely operable from the first floor without the necessity of ever climbing to the upper floors.

These are but examples of refinements which can be added to my invention without departing from its principles. Such modifications are to be considered as included in the hereinafter appended claims unless these claims by their language expressly state otherwise.

I claim:

1. In a multiple floor feeder, the combination comprising: a feed hopper on the bottom floor; an elevator, said elevator extending through at least one upper floor; first means for distributing feed on said bottom floor; a first conveyor associated with said feed hopper and first said distributing means; said first conveyor simultaneously discharging into both said first distributing means and said elevator; a second distributing means on said upper floor; the discharge end of said elevator discharging into said second distributing means; a second conveyor associated with said second distributing means; a return means including a chute for returning feed to said feed hopper; said second conveyor discharging into said chute.

2. In multiple floor feeder, the combination comprising: a feed hopper on the bottom floor; an elevator, said elevator extending through at least one upper floor; first means for distributing feed on said bottom floor; a first conveyor associated with said feed hopper and first said distributing means; said first conveyor discharging into both said first distributing means and said elevator; a second distributing means on said upper floor; the discharge end of said elevator discharging into said second distributing means; a second conveyor associated with said second distributing means; a return means including a chute for returning feed to said feed hopper; said second conveyor discharging into said chute; a first gate adjacent said first conveyor and a second gate adjacent said second conveyor; said gates being adapted to regulate the quantity of feed removed from said conveyors by said distributing means.

3. In a multiple floor feeder, the combination comprising: a hopper on the bottom floor; said hopper having a feed bin; an elevator extending up through said floors; a conveyor for removing feed from said feed bin; said conveyor discharging into the lower end of said elevator; a distribution unit on each of said upper floors; a distribution chamber in each of said distribution units; said upper end of said elevator adapted to discharge into the distribution chamber of the distribution unit on said upper floors; return means including a chute for returning feed to said feed bin; means providing communication between said chute and the distribution chambers of each of said distribution units; a distribution conveyor in each of said distribution chambers; the discharge end of each of said distribution conveyors communicating with said chute; means associated with each of said distribution chambers for withdrawing, between the ends of said distribution conveyors, measured quantities of feed from each of said distribution chambers.

4. In a multiple floor feeder, the combination comprising: a hopper on the bottom floor; said hopper having a feed bin; an elevator extending up through said floors; a conveyor for removing feed from said feed bin; a distribution unit on each of said upper floors; a dis-

tribution chamber in each of said distribution units; the discharge end of each of said distribution conveyors communicating with said chute; means associated with each of said distribution chambers for withdrawing, between the ends of said distribution conveyors, measured quantities of feed from each of said distribution chambers.

tribution chamber in each of said distribution units and in said hopper; a distribution conveyor in each of said distribution chambers; the distribution conveyor in the distribution chamber of said hopper being tandemly aligned with the conveyor in said feed bin; said conveyor in said feed bin discharging to said distribution conveyor; said distribution conveyor discharging into the lower end of said elevator; said upper end of said elevator adapted to discharge into the distribution chamber of the distribution unit on the top one of said upper floors; a return means including a chute for returning feed to said feed bin; means providing communication between said chute and the distribution chambers of each of said distribution units; the discharge end of each of said distribution conveyors in said distribution units communicating with said chute; means associated with each of said distribution chambers for withdrawing between the ends of said distribution conveyors measured quantities of feed from each of said distribution chambers.

5. In a multiple floor feeder, the combination comprising: a hopper on the bottom floor; said hopper having a feed bin; an elevator extending up through said floors; a conveyor for removing feed from said feed bin; said conveyor discharging into the lower end of said elevator; a distribution unit on each of said upper floors; a plurality of carrier means associated with each of said distribution units and with said hopper for removing measured quantities of feed therefrom; a return chute; means providing communication between said chute and each of said distribution units; a return conveyor mounted 30 on said hopper; said return chute discharging into said return conveyor; said return conveyor discharging into said feed bin; the upper end of said elevator discharging into the top of said return chute; a movable baffle in said return chute at each of said distribution units for by-passing said distribution unit or for deflecting feed

5

from said return chute into the adjacent of said distribution units; conveyor means in each of said distribution units for distributing feed to each of said feed carrier means; the discharge ends of each of said conveyor means communicating with said return chute.

6. In a multiple floor feeder, the combination comprising: a hopper on the bottom floor; said hopper having a feed bin; an elevator extending up through said floors; a conveyor for removing feed from said feed bin; said conveyor discharging into the lower end of said elevator; a distribution unit on each of said upper floors; a plurality of chains passing through each of said distribution units and through said hopper for removing measured quantities of feed therefrom; means including a chute for returning feed to said feed bin; means providing communication between said chute and each of said distribution units; a return conveyor mounted on said hopper; said chute discharging into said return conveyor; said return conveyor discharging into said feed bin; the upper end of said elevator discharging into the top of said chute; a movable baffle in said chute at each of said distribution units for by-passing said distribution unit or for deflecting feed from said chute into the adjacent of said distribution units; conveyor means in each of said distribution units for distributing feed to each of said chains; the discharge end of each of said conveyor means communicating with said chute.
